UNITED STATES PATENT OFFICE.

FRANCIS ST. AMANT, OF BOSTON, MASSACHUSETTS.

PIANO-ACTION.

SPECIFICATION forming part of Letters Patent No. 293,369, dated February 12, 1884.

Application filed November 22, 1882. (No model.)

To all whom it may concern:

Be it known that I, FRANCIS ST. AMANT, of Boston, in the county of Suffolk and State of Massachusetts, a subject of Victoria, Queen 5 of England, &c., have invented a new and useful Improvement in Grand or Square Piano-Forte Actions, of which the following is a full, clear, and exact description, reference being had to the accompanying drawings, forming 10 a part of this specification, in explaining its nature, in which—

Figure 1 represents in side elevation an action containing my invention, showing the hammer at rest. Fig. 2 represents the position of the parts of the action immediately 15 after the string has been struck. Figs. 3 and 4 represent in perspective details, hereinafter referred to.

This invention is an improvement upon that 20 described in my Letters Patent No. 201,461, dated March 19, 1878. In said patent I describe a piano-action which is substantially all that is desired, except in one particular, and that is the connection between the hammer-elevator and the hammer stem or flange. The 25 connection represented in the patent consists of a projection on the hammer-elevator, covered with leather, felt, or other flexible or soft material, and a wooden surface or shoe on the 30 hammer, which rests on the projection on the hammer-elevator, and receives the impulse from it. The projection, however, on account of the hard usage to which it is submitted, soon wears off and causes a change in the relative 35 position of the parts of the action to such an extent that its efficiency is impaired, and it is not easily put in order again, it being necessary to renew some of the parts, and generally to overhaul the entire action to put it 40 in good working condition. Moreover, it requires considerable skill and expenditure of labor and material to properly adjust the relative position of the hammer-elevator to the hammer stem or flange in the first instance. I 45 have ascertained, however, that by interposing an adjustable metallic connection between the hammer stem or flange and the hammer-elevator that these objections are entirely obviated, so that if from wear or any other reason 50 the action needs setting up it can be done by means of this adjustable device, and the action is also correspondingly improved.

Referring to the drawings, A is the hammer stem or flange.

B is the hammer-elevator, which is operated 55 in the manner described in said patent.

C is the interposed regulating device. It is preferably made of iron or steel, with a head, c, rounded or curved upon its contacting-surface, and a shank, c', having a screw-thread, c''. When this device is attached to the hammer-elevator, it is screwed into the projecting portion b thereof. The head has recesses c', for the reception of a spanner, whereby it may be turned and the position of 60 the head in relation to the hammer-elevator varied. When the regulating device is attached to the hammer-stem or flange, its shank projects through the hammer-spindle, as shown in Fig. 4, and a recess, c', is cut across its end 65 for the reception of a screw-driver. The portion of the action with which the rounded head comes in contact should also be rounded, and preferably should be of some flexible or soft material, like felt or leather. For the best 70 effect it is perhaps desirable that the regulating device be applied to the hammer-elevator.

By making the upper surface of the device rounded or curved there is less friction between the parts, and by making it of metal 80 great durability and strength in a light and compact form are obtained.

Having thus fully described my invention, I claim and desire to secure by Letters Patent of the United States—

85

1. The combination, in a piano-forte action, of the hammer-stem, the hammer-elevator B, and the interposed adjustable regulating device C, made of metal, and having the regularly rounded or curved head c and the threaded shank c', all substantially as described.

2. The combination of a hammer-stem, the hammer-elevator B, and the curved or rounded metallic bumper C, arranged between the hammer-stem and the hammer-elevator and fastened to one of them, and adapted to contact with a rounded or curved leather or cloth-covered bumper or projection upon the other, all substantially as and for the purposes described.

FRANCIS ST. AMANT.
